his attorney

UNITED STATES PATENT OFFICE.

MILLARD A. LUCAS, OF KNOXVILLE, TENNESSEE.

WORKMAN'S TIME CALCULATOR.

Application filed May 3, 1921. Serial No. 466,379.

To all whom it may concern:

Be it known that I, MILLARD A. LUCAS, a citizen of the United States, residing at Knoxville, in the county of Knox and State 5 of Tennessee, have invented new and useful Improvements in Workmen's Time Calculators, of which the following is a specification.

This invention relates to calculators, and 10 the prime object is to provide an improved device particularly adapted for use in mechanically calculating and indicating the exact amount of time between any two given times, as for instance, between the time of 15 going to work and the time of stopping work, whereby the device is particularly adapted for the use of timekeepers in factories and other places having a great many employees. The device is arranged to indicate 20 not merely the lapsed time but the actual time of work where time is taken out for lunch, dinner, or other purposes, thereby avoiding the laborious work of counting up the hours and fractions thereof, as is commonly 25 done in factories and the like.

With these and other objects in view, the present invention consists in the combination and arrangement of parts as will be hereinafter more fully described, shown 30 in the accompanying drawings, and particularly pointed out in the appended claim, it of course being understood that changes in the form, proportion, size and minor details may be made, within the 35 scope of the claim, without departing from the spirit or sacrificing any of the advantages of the invention.

In the drawing:

Figure 1 is a plan view of a time calculator embodying the features of the present invention.

Figure 2 is a cross-sectional view thereof.

The present embodiment of the invention includes a base or body A which may be of 45 any shape, but is preferably circular and provided with a circular time scale divided into hours and fractions thereof, with the hour gradations numbered from 1 to 12, as in an ordinary clock dial. This body 50 is provided with a concentric circular depression in which is rotatably mounted a disk B provided with an outer circular time scale C and an inner circular time scale D, the hour designations of the inner scale 55 being placed midway between the hour designations of the outer scale. The hour des-

ignation 12 of the inner scale is located midway between the hour designations 12 and 1 of the outer scale. The disk may be rotatably mounted in any suitable manner, 60 the mounting shown in the drawing being that of a pivot E rising from the base A and having the disk B rotatable thereon. A movable index F is mounted to travel in a circular path around the several scales, and 65 in the present embodiment of the invention is shown as a radial arm mounted upon the pivot E and extending across the several scales. A stationary pointer or index G is provided upon the rotatable disk, is located 70 on the hour designation 12, and overlaps and cooperates with the time scale on the body A.

The device is used in the following manner. Assuming that a workman goes to 75 work at 7 o'clock, the rotatable scale member is moved to bring its index or pointer G into alignment with the hour designation 7 on the stationary scale. Further assuming that the workman stopped work at 2 80 o'clock, the radial arm or index F is swung around to the hour designation 2 on the stationary scale. It will now be noted that the movable index F is in alignment with the hour designation 7 of the outer scale 85 of the rotatable member B, which indicates that seven hours have elapsed from 7 o'clock to 2 o'clock, which is the exact time between said hours. Assuming that the workman took out a predetermined amount of 90 time, (in the present instance half an hour for lunch, dinner or the like), by reference to the inner scale on the rotatable member B it will be noted that the movable index F is half way between the hour designations 95 6 and 7, thereby indicating that the exact amount of time the workmen worked was six and a half hours.

From the foregoing description it will be understood that all that the timekeeper has 100 to do is to set the index G at the hour the workman went to work and subsequently move the movable index to the hour indication on the outer stationary scale, at which the workman stopped work, and then 105 the total time as well as the time of actual work will be plainly indicated on the scales without any mental effort or mental calculation whatsoever.

Of course it will be understood that any 110 number of time divisions may be employed between the hour designations, and that the

inner scale on the movable member B may be arranged, with respect to the outer scale thereon according to the amount of time which is to be taken out for lunch or other 5 purposes.

What I claim is:

A calculator comprising a body having a circular time scale, a rotatable member mounted concentrically within said scale 10 and provided with two concentric time

scales, the hour designations of the inner scale lying between the hour designations of the outer scale of the movable member, a pointer carried by the movable member and in cooperative relation with the scale of the 15 body, and a movable index extending radially across the several scales and movable in a circular path around said scales.

MILLARD A. LUCAS.
